UNITED STATES PATENT OFFICE

165,565

LIPSTICK TRAY

Virginia Alice White, Dallas, Tex.

Application December 21, 1950, Serial No. 13,523

Term of patent 14 years

(Cl. D86—10)

To all whom it may concern:

Be it known that I, Virginia Alice White, a citizen of the United States, residing at Dallas, in the county of Dallas and State of Texas, have invented a new, original, and ornamental Design for a Lipstick Tray, of which the following is a specification, reference being had to the accompanying drawing, forming part thereof.

I claim:

The ornamental design for a lipstick tray, as shown.

VIRGINIA ALICE WHITE.
